EVAPORATOR

Franklin G. Slagel, Buffalo, N. Y., assignor to
 Feeders Manufacturing Company, Inc., Buffalo,
 N. Y., a Corporation of New York

Application May 13, 1929, Serial No. 362,806
 Renewed January 10, 1933

8 Claims. (Cl. 62—126)

This invention relates to mechanical refrigerating systems and more particularly to evaporators of the flooded type.

Evaporators employed with refrigerating systems of the flooded type usually comprise a header from which tube loops or the equivalent depend, the refrigerant and oil which travel together in cycle through the system being maintained in a body filling the tubes and a portion 10 of the header. The oil is partially or wholly miscible in the refrigerants commonly used, so that oil builds up in the top of the tubes through release of the refrigerant when gasified. Such accumulation of free oil in the 15 tubes retards the rise of gasified refrigerant therethrough, as well as preventing or retarding the flow of liquid refrigerant into the tubes, so that the transfer of heat through the tubes is inefficient.

20 An object of this invention is to improve the efficiency of evaporators through the above causes, by the provision of means associated therewith to induce circulation in the tubes.

Another object of my invention is to provide 25 an evaporator in which liquid refrigerant is moved to the lower portion of depending tubes by a siphon action.

A further object of my invention is to improve 30 the heat transfer efficiency of an evaporator of the flooded type in which tubes depend from a header and contain liquid refrigerant and oil.

A further object of my invention is to provide 35 a shield for the open float of an evaporator valve controlling mechanism, so that the liquid particles freed by contact of liquid refrigerant entering the refrigerant body of higher temperature in the evaporator will not travel into the float and be moved into the return tube.

In the accompanying drawing, Fig. 1 is an 40 end view of an evaporator with which my invention is incorporated, portions of the evaporator and tubes being broken away.

Fig. 2 is a side elevation of the evaporator, 45 a portion of the header being broken away.

Fig. 3 is a fragmentary plan view of the float for controlling the valve mechanism in the 50 evaporator.

Referring now to the drawing by characters of reference, 10 represents a cylindrical evaporator header having an integral end 11 and a sealed end 12. Depending from the header are two parallel longitudinal rows of tube loops 13, the loops extending transversely of the header and having their open ends secured to and in 55 open communication with the header. The ends

of the inner legs 14 of such loops are in a plane below the ends of the outer legs 15, so that circulation is induced downwardly in the inner legs and upwardly in the outer legs. In addition to the loops 13, I provide outer loops 16 which extend longitudinally of the header and exteriorly of the rows of loops, the open ends of the loops 16 extending through and being sealed to the header in a plane above the ends of the legs 15.

The header is adapted to contain a body of liquid refrigerant and oil, the upper level of which is indicated at 17, and the open ends of the legs 15 are partially above such level while the ends of the legs 14 and the loops 16 are below the level of the body. It will therefore be seen that a portion of the header and the loops contain liquid refrigerant and oil.

The end 12 of the header supports interior valve mechanism which controls the inlet 18 leading from the condenser of the refrigerating system (not shown). A valve seat member 19 is arranged in the inlet opening 20 and the valve member 21 is arranged to engage the seat member. The valve member is automatically actuated by the open vessel 22 which floats upon the liquid body in the header. As the liquid level falls the float moves downwardly permitting the refrigerant and oil in the inlet conduit 23 to open the valve and flow into the header until the body level in the header to a point where the float forces the valve member against the valve seat thus stopping the inflow. An outlet tube 9 extends into the float and oil and gasified refrigerant is drawn by vacuum therefrom and from the header through the return conduit 24 leading to the compressor (not shown).

When liquid refrigerant from the condenser enters the body of warmer liquid refrigerant in the header there is a turbulence or severe boiling created which causes liquid refrigerant particles to move swiftly into the vapor space above the inlet. In order to prevent such liquid particles from gathering in the open float, I bend the upper portion of the adjacent float wall outwardly to form a baffle or shield 25. Thus movement of such free liquid refrigerant particles into the return conduit is prevented and the frosting thereof from this cause is eliminated. Further the float is not affected in its normal movement to control the valve, due to the collection therein of such free liquid particles.

When the oil is miscible either entirely or partially with the refrigerant, gasification of the refrigerant in the tube loops frees a pro-

- portionate quantity of oil which will collect in the tube loops and retard or trap refrigerant travel into and gasified refrigerant travel from the tube loops. With methyl chloride and oil which are wholly miscible together, low temperatures change the viscosity of the oil so that it becomes sluggish in the tube loops when the methyl vaporizes and will retard or prevent escape of gas or liquid therethrough, thus affecting materially the heat transfer efficiency of the tube portion of the evaporator. Likewise, with refrigerants such as sulphur dioxide, the oil released by the gasified refrigerant in the tubes will collect with the same result as with methyl chloride.
15. In order to materially reduce such inefficiency through oil binding in the tubes, I provide means through which liquid refrigerant can flow from the header to the bottom of the tubes. To this end, I provide pipes 30 which extend from the interior of the header to the lowermost portion of the tube loops 13. The pipes 30 are open at both ends and are arranged to extend through the inner legs 14 of the tube loops with the upper ends submerged in the body of liquid in the header and with the lower ends extending to substantially the center of the loop bends. Irrespective of the oil accumulation in the tube loops which normally retards escape of refrigerant gas to the vapor space in the header, liquid refrigerant will flow through the pipes 30 to the bottom of the loops from the liquid body in the header because of the head pressure. A supply of liquid refrigerant to the bottom of the tubes being thus assured, it will vaporize and force its way up through the legs of the tubes much faster under oil bound conditions than would normally occur. Other gas trapped in the tubes will also be released with the gas of the refrigerant entering through the pipes, and as a result the oil in the tubes will be agitated to a greater extent so that gas flow is generally more free. Circulation in the tube loops is in this manner assured because the circulation is accelerated and oil retardation is lessened, thus resulting in more efficient heat transfer from the tube loops.
20. A sheet brace member extends in intimate metallic contact with and between the legs 14, being welded or secured in some similar manner. The brace member terminates in a bottom flange 33 which is secured to the tube loops by a strip of metal 34. This brace member and its relation with the tube loops provides rigidity and a heat transfer for the loops of the evaporator.
25. Various changes can be made in the details of the structure described without departing from the spirit of the invention and the scope of what is claimed.
30. What I claim is:
1. In an evaporator adapted to contain a body of liquid refrigerant and oil, a header, tube loops depending from the header and in open communication therewith at both ends, and siphon tube means for inducing circulation of refrigerant in a definite direction in the tube loops, said tube means extending through a portion of the tube loop and having its upper end submerged in the liquid in the header. 80
  2. In an evaporator adapted to contain a body of liquid refrigerant and oil, a header, tube loops depending from the header and in open communication therewith, and an open pipe extending through one leg of the tube loops and into the header. 85
  3. In an evaporator adapted to contain a body of liquid refrigerant and oil, a header, U shaped tube loops depending from the header and in open communication therewith, and separate tube means establishing communication between the liquid in the header and the bottom portion of the tube loops, said tube means extending through one leg of the loops. 90
  4. In an evaporator adapted to contain a body of liquid refrigerant, a header, a tube loop extending at least partially below the header and open at both ends and communicating therewith, and tube means having open ends establishing communication between the liquid in the header and the lowermost portion of the tube loop, said tube extending through one end of the tube loop. 100
  5. In an evaporator adapted to contain liquid refrigerant and oil, a header, tube loops extending below and in open communication with the header, and a pipe extending through one leg of a tube loop, the end of the pipe being curved downwardly in the header and open at both ends. 110
  6. In an evaporator adapted to contain liquid refrigerant and oil, a header, tube loops arranged in two parallel rows, and pipes extending from the header through the inner adjacent legs of the parallel tube loops, said pipes being open at both ends and arranged to induce movement of gasified refrigerant upwardly through the outer legs of the parallel tube loops. 115
  7. In an evaporator adapted to contain a body of liquid refrigerant and oil, a header, an open float, and float actuated means for automatically controlling the inlet to the header to maintain a constant body of liquid therein, said float having a shield extending from the side thereof above the header inlet. 125
  8. In an evaporator adapted to contain a body of liquid refrigerant and oil, a header, a refrigerant inlet in the header wall, valve mechanism controlling the inlet, and an open float in the header actuating the valve mechanism, the wall of said float adjacent the inlet being turned outwardly at the top in a plane above the inlet. 130
  9. In an evaporator adapted to contain a body of liquid refrigerant and oil, a header, a refrigerant inlet in the header wall, valve mechanism controlling the inlet, and an open float in the header actuating the valve mechanism, the wall of said float adjacent the inlet being turned outwardly at the top in a plane above the inlet. 135

FRANKLIN G. SLAGEL.
